Attorney

UNITED STATES PATENT OFFICE

MORRIS FALKOVITZ, OF PHILADELPHIA, PENNSYLVANIA

POCKET CONSTRUCTION FOR TROUSERS

Application filed March 10, 1928. Serial No. 260,777.

REISSUED

The present invention relates to pockets for trousers and has for its principal object to provide a tape about the connected edges of the pocket, suitably secured thereto to form 5 a closure for one edge of the pocket and utilizing the same tape attaching means for securing the pocket to the garment along another of the edges of said pocket.

Another object of the invention is to arrange 10 a tape about one of the connected edges of the pocket material which is subjected to the greatest amount of wear to provide a seam for such edge of the pocket which is as strong and durable as the usual tailor's pocket and as 15 inexpensive and easily formed as the usual machine pocket.

A still further object of the invention is to provide a pocket structure in which the steps necessary for securing the same in a proper 20 position to the garment are materially reduced whereby to permit the manufacture of the garment in a more economical and expeditious manner.

Other objects and advantages reside in the 25 special construction and combination of the various elements comprising the invention, reference being had to the accompanying drawings forming a part hereof, wherein:—

Figure 1 is a perspective view of the portion 30 of a garment having a pocket opening illustrating the manner in which the pocket is secured in position about the edges of such opening.

Figure 2 is a transverse sectional view 35 through the pocket and section of the garment with which the same is attached, and

Figure 3 is a sectional view through the bottom edge of the pocket taken along a line 3—3 of Figure 1.

Referring now to the drawing in detail, I have shown my invention arranged to be used upon a pair of trousers composed of a series of interconnected sections indicated at 5 and having their adjacent edges turned inwardly 45 to form folds 6 and having their inturned folded sections secured by sewing threads 7 therethrough. The connected edges of the garment section thus form a seam as clearly shown in Figure 1 of the drawing.

Arranged under one of the folded edges 6

is a strip of material 8 secured adjacent one edge thereof to said folds by the same stitching 7 provided for connecting the sections of the garment to each other. The other folded edge 6 of the opposite garment 6 terminates 55 slightly below the upper edge of the garment at a point adjacent the top of the pocket opening which is formed by a break in the seam, said break occurring for a suitable distance to provide a pocket opening of conventional and appropriate size. 60

The edge of the garment section extending along such break in the seam is folded inwardly as shown at 9 as attached thereto one edge of a strip of material 10, suitably secured by a row of stitching 11, said strip being folded back upon itself in a direction toward the interior of the pocket opening. 65

A garment pocket 12 of the usual shape is secured about the edges of said pocket opening, said pocket, as clearly illustrated in Figure 1 of the drawing, being formed of a section of material folded upon itself with one of its edges indicated at 13 being disposed in alignment with the inturned edges of the fold 70 9 and material strip 10. The threads 11 extend entirely through the adjacent end 13 of the pocket and the folds 9 and 10 whereby to secure the same to each other as clearly shown in Figure 2 of the drawing with the strip of material 10 extending inwardly between the folds of the pocket 12 and secured to its adjacent side thereof by a row of stitching 14. 75 80

The other edge of the pocket 12 is arranged in alignment with the free edge of the strip of material 8 and is secured in position thereto by means of a strip of tape 15, the edges of the tape being folded inwardly in a manner well known in the art, the tape being secured in position about the edge of the pocket 12 and strip 8 by a row of stitching 16 which extends entirely through the fold of the tape as well as the edges of the pocket and strip. 85 90

As clearly shown in Figure 1 of the drawing the tape 15 extends entirely along the edge of the pocket disposed adjacent the strip 8 and also entirely along the under side thereof, thereby serving to close the bottom edge of the pocket as well as the side of the same. 95

The edge of the pocket 12 to which the tape 100

15 is attached extends slightly beyond the opposite edge 13 of the pocket and in order to hide the fold 6 and edge of material 8 alined therewith adjacent the pocket opening I provide a connecting piece of material 17 having one edge 18 folded against the fold 6 and secured thereto and also to the adjacent edge of the strip of material 8, by means of a row of stitching 7, which thereby provides a seam 10 along one edge of the pocket opening. The opposite edge of the strip 17 extends inwardly of the pocket and is folded backwardly upon itself against the inner surface of the pocket and secured thereto by a row 15 of stitching 19, which stitching, it is apparent, may extend throughout the length of the strip and across the lower edge thereof. The strips 8 and 17 are secured at their upper edges to the pocket material by the row of 20 stitching 20.

After the pocket has been secured in position about the pocket opening in the manner indicated the upper edge of the material forming the pocket 12 is secured by a row of 25 stitching 20.

It will thus be apparent that the pocket is entirely closed except by way of the pocket opening formed in the seam between the two sections of the garment material.

30 Furthermore as clearly shown in Figure 1 of the drawings it will be apparent that the bottom edge of the pocket and one edge of the pocket material is closed by the tape by a single row of stitching which is utilized to 35 attach the same to the pocket at the same time the edge of the pocket is secured to the strip of material 8 by means of which the pocket is attached to the garment.

40 This manner of closing the bottom edge of the pocket and at the same time securing one of its side edges to the garment eliminates the necessity of several separate sewing operations which are usually required in a pocket construction and in addition no loose edges 45 of the pocket material are formed within the pocket, as is present in the usual tailor made pocket, and which is objectionable because of its tendency to unravel and collect loose dirt about the seam of the pocket material. The 50 manner in which the tape serves to eliminate these loose edges of the pocket material is clearly illustrated in Figure 3 of the drawing.

55 It is obvious that the invention is susceptible of various changes and modifications, without departing from the spirit or scope of the invention or sacrificing any of its advantages, and I accordingly claim all such forms of the device to which I am entitled.

Having thus described my invention, what 60 I claim as new is:

65 In a pocket structure, a garment having a pocket opening formed at the adjoining edges of a pair of the sections of the garment material, the marginal portion of said material within the opening being folded inwardly

and rearwardly upon itself, a section of pocket material folded upon itself with its open side edges disposed at the respective sides of the pocket openings, a pair of strips of fabric disposed with one edge at opposite sides of the garment material at one edge of the pocket opening, one of said strips having a folded marginal portion within the adjacent folds in the material edge, the other of said strips having a folded back portion abutting the folds in the material edge, said strips having their opposite edges secured to one side of the pocket material, and a single row of stitching provided for securing the sections of the garment material to each other and for securing the edges of the pair of strips to one edge of one of the garment sections at one edge of the pocket opening, said stitching extending through the fold line of the strip and the material, the other of said side edges of the pocket material being attached directly to the outer section of the garment of the pocket opening, and said pair of strips of material being adapted to lie flat against the pocket material and extended in opposite directions from their garment attached edge.

In testimony whereof I affix my signature,
MORRIS FALKOVITZ.
